UNITED STATES PATENT OFFICE.

BERNARD SPOONER, OF BROOKLYN, NEW YORK, ASSIGNOR TO AMERICAN ARMOR CORPORATION, OF NEW YORK, N. Y., A CORPORATION OF DELAWARE.

BULLET-PROOF ARMOR.

Application filed March 27, 1924. Serial No. 702,213.

To all whom it may concern:

Be it known that, I BERNARD SPOONER, a citizen of Austria, and a resident of Brooklyn, in the county of Kings and State of New York, have invented certain new and useful Improvements in Bullet-Proof Armor, of which the following is a specification.

This invention relates to improvements in bullet-proof armor adapted for shielding 10 persons and objects subjected to the hazard and danger of gun fire.

The principal object of the invention is to provide a shield for the body that can be worn under the ordinary outer clothing 15 of an individual in an unobtrusive manner and which is sufficiently light in weight and also flexible as to avoid discomfort and at the same time effectually protect the wearer from injury due to the impact of a bullet.

Another purpose is to produce a shield 20 composed of superposed steel plates, each having an outer cushion surface and so arranged as to present a multiple layered structure secured to a cushion adjacent the body.

A further aim is in the provision of fabric 25 covering containing pockets for the armor plates whereby they are held in operative position and not readily liable to disarrangement.

These objects, which also include similarly 30 constructed armor structures applicable to vehicles, cashiers' cages, and the like, are accomplished by the novel construction and arrangement of parts hereafter described 35 and shown in the annexed drawing, forming a material part of this disclosure, and in which:—

Figure 1 is a front elevational view of an embodiment of the invention, parts being 40 broken away to disclose the construction.

Figure 2 is a fragmentary longitudinal sectional view of the same, drawn to an enlarged scale.

Figure 3 is a diagrammatic sectional view 45 showing the structural features of the casting.

Figure 4 is a similar view showing a modified form of construction.

Figure 5 is an edge view of one of the 50 plate inserts as corrugated.

Figure 6 is a plan view of the same.

The armor plate as shown in the drawing consists essentially of a plurality of steel strips 10 representing an oblong rectangle

in profile, uniform in thickness and width 55 and of such length as may be convenient.

These strips are given a spring temper and treated in such manner as to render them rust-proof or they may be electro-plated.

Disposed on the outer sides of each plate 60 are sheets of cork 11 of the same size as the plates, acting to prevent noise and the conduction of moisture to the plates.

These plates and sheets are entered into 65 pockets formed of a strong close woven textile fabric 12, each pocket being complete in itself, the bight or folded portion 13 extending downward and the upper edges being secured by stitches 14 to the next adjacent pocket, all of which are of unitary 70 construction, made from a single piece of fabric.

The next adjacent lower pocket has its 75 outer member 15 secured by the row of stitches 14 and extend so that slightly less than one third of its width is below the overlying portion of the next outer pocket, the arrangement being such that three thicknesses of the steel and cork, except at the extreme top, are presented to protect the wearer, these several pockets overlapping in the manner of the scales of a fish or shingles as laid upon the roof of a building, affording a laminated structure, non-penetrative to an 80 ordinary bullet.

At the back of these pockets and secured by such stitching as may be necessary, is a felt blanket or quilt 16 composed of hair, camel's hair being preferred as not readily ignited and because of its pronounced wearing qualities.

This sheet of camel hair felt rests against a sheet of cork 17 which comprises the inner wall of the structures.

Figure 4 shows a structure in which the 95 pockets 18 are stitched across at their upper ends, as at 19, no flap being used. In all cases the pockets are secured at their ends, after the inserts have been entered, by a row of 100 stitches 20.

On Figures 5 and 6 it is shown that the steel plates may be corrugated to present regular undulations 21, the same obviously strengthening the same in lengthwise direction and these corrugated plates may be 105 covered with cork as before described.

From the foregoing it will be seen that the structure is readily foldable and due

to the resiliency of the elements, may be bent to conform to whatever body it is desired to protect.

It will be understood that the disposition of the cork is such as to prevent glancing or ricochetting of a bullet if fired at an angle, that the camel hair felt cushion absorbs and reduces shock and that the inner cork lining acts as a non-conductor for heat, presenting a comfortable feeling.

Although I have described my improvements with considerable detail and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A bullet-proof armor comprising a plurality of textile fabric pockets arranged in overlapping relation, a resilient strip of steel in each pocket, a sheet of cork disposed in intimate relation over each steel strip, and a cushion backing against which all of said pockets make contact.

2. A bullet-proof armor comprising a plurality of textile fabric pockets arranged in overlapping relation lengthwise the armor, a noncorrodible sheet of steel in each pocket, a layer of cork superposed on each steel sheet, and a camel hair felt cushion secured to the back of the armor in contact with each pocket.

3. A bullet-proof armor comprising a plurality of textile fabric pockets arranged in overlapping relation lengthwise the armor, said pockets being formed from a

single piece of material, a noncorrodible steel sheet in each pocket, a layer of cork superposed on each steel sheet, a felted hair cushion at the back of the armor in contact with all of said pockets, and a cork lining secured exteriorly said cushion. 45

4. A bullet-proof armor comprising a plurality of relatively narrow longitudinal pockets composed of a single piece of textile fabric and articulated at their upper edges 50 to extend partially over pockets adjacently below, a spring steel plate filling each pocket, a cork sheet overlying each plate, and a sheet of felted hair arranged in intimate contact with the exposed rear sides of said 55 pockets.

5. A bullet-proof armor comprising a plurality of relatively narrow longitudinal pockets composed of textile fabric and articulated at their upper edges to extend 60 partially over pockets adjacently below, a spring steel plate filling each pocket, a cork sheet overlying each plate, a second cork sheet forming a backing for the armor, and felted hair interposed between the last 65 named cork sheet and said pockets.

6. A bullet-proof armor comprising a plurality of relatively narrow pockets arranged in triple overlapping relation, said 70 pockets being composed of firm textile fabric and attached at their upper edges, a compound filler in each pocket, said filler consisting of steel and cork plates juxtaposed, the cork plate being outermost, means for securing said plates in position, and a cushion 75 composed of hair overlaid with cork, at the back of said pockets.

In testimony whereof I have signed my name to this application.

BERNARD SPOONER.
